UNITED STATES PATENT OFFICE

152,241

DESIGN FOR AN AMUSEMENT MACHINE
CABINETEdward J. Collins, Brentwood, Los Angeles, Calif.,
assignor to Raymond T. Moloney, Chicago, Ill.

Application June 20, 1947, Serial No. 139,833

Term of patent 14 years

(Cl. D34—5)

To all whom it may concern:

Be it known that I, Edward J. Collins, a citizen of the United States, residing in Brentwood, Los Angeles, in the county of Los Angeles, and State of California, have invented a new, original, and ornamental Design for an Amusement Machine Cabinet, of which the following is a specification, reference being had to the accompanying drawings, forming a part thereof.

Figure 1 is a perspective view of an amusement machine cabinet incorporating my new, original, and ornamental design.

Figure 2 is a front elevational view thereof.

Figure 3 is a rear elevational view thereof.

Figure 4 is a top plan view thereof.

Figure 5 is a side elevational view thereof.

I claim:

The ornamental design for an amusement machine cabinet, substantially as shown.

EDWARD J. COLLINS.
